DESIGN FOR A CUT-OUT FIGURE OR THE LIKE

Ashton B. Collins, Birmingham, Ala.

Application October 27, 1934, Serial No. 53,794

Term of patent 14 years

To all whom it may concern:

Be it known that I, Ashton B. Collins, a citizen of the United States, residing at Birmingham, in the county of Jefferson and State of Alabama, have invented a new, original, and ornamental Design for a Cut-Out Figure or the like, of which the following is a specification, reference being had to the accompanying drawing, forming part thereof.

I claim:—

The ornamental design for a cut-out figure or the like, as shown.

ASHTON B. COLLINS.
